UNITED STATES PATENT OFFICE.

WALTER E. ERWIN, JOSEPH N. LLOYD, MATTHEW D. MANN, JR., AND RAYMOND L. WINCHELL, OF SANTA BARBARA, CALIFORNIA.

DOOR-OPERATING MECHANISM FOR CARS AND THE LIKE.

1,142,408.

Specification of Letters Patent.

Patented June 8, 1915.

Application filed September 29, 1914. Serial No. 864,044.

To all whom it may concern:

Be it known that we, WALTER E. ERWIN, JOSEPH N. LLOYD, MATTHEW D. MANN, JR., and RAYMOND L. WINCHELL, citizens of the United States, and residents of Santa Barbara, Santa Barbara county, California, have invented new and useful Improvements Relating to Door-Operating Mechanism for Cars and the like, of which the following is a specification, reference being had to the accompanying drawings, in which—

Figure 1 is a section through the center of a car, showing the doors on one side of the car opened by our mechanism; Fig. 2 is an elevation partly in section, showing the doors on one side of the car in closed position; Fig. 3 is a plan view showing the lever mechanism controlling the opening of the doors; Fig. 4 is a plan view of our door operating mechanism on an enlarged scale in position when the doors on both sides of the car are closed; Fig. 5 is a plan view similar to Fig. 4 but showing the position of our operating mechanism when the doors on one side of the car are open, Fig. 6 is a sectional plan view showing the screw arrangement which moves the operating levers; Fig. 7 is an elevation of that portion of our mechanism shown in Fig. 6; Fig. 8 is a sectional view on the line VIII—VIII of Fig. 6; and Fig. 9 is a sectional view similar to Fig. 8 but showing the operating levers in locked position.

Our invention has to do with cars in which doors are positioned directly opposite each other, and provides a simple mechanism whereby either the doors on both sides of the car or the doors on one side or the other of the car may be opened through the movement of a single control handle.

Referring to the drawings, in which a preferred form of our invention is shown, 2 is a car body of ordinary construction, having on both sides doors 3. In the embodiment of our invention shown in the drawings one set of doors 3 is intended to be used for the entrance of passengers, and one set as an exit. It is apparent, however, that in place of the small folding doors shown various other types of folding or sliding doors may be substituted. As shown in the drawings, the entrance and exit doors 3 are separated by

posts, or columns 4, one being positioned on each side of the car. Running between the posts 4 is a hollow shaft case 5, which is divided into two portions, between which is a considerable gap, as shown in Fig. 5. The two parts of the shaft case 5 are connected by the bracket 6. The bracket 6 is supported by a column 7, which runs from the floor of the car, and may carry a fare box 8. Within the shaft case 5 runs a shaft 9, having near its ends right and left hand threaded portions one of which is designated in Fig. 6 by the numeral 10. Each of the right and left hand threaded portions of the shaft 9 screws into a female screw, one of which is designated by the numeral 11 in Fig. 6. Extending from the female screw 11 are lugs 12, and extending from the screw corresponding to the female screw 11 (which is not shown in the drawings) are lugs 13. The lugs 12 slide in slots 14 in the shaft case 5, and the lugs 13 slide in corresponding slots in the other half of the shaft case 5.

Pivoted to the lugs 12 are connecting rods 15, arranged to move the lever arms 16. The lever arms 16 are keyed to shafts 17, which carry the two doors 3, which are nearest to the post 4. The two doors 3 farthest away from the post 4 are carried by shafts 18 and are operated by the lever arms 21.

Pivoted to the lugs 13 are connecting rods 22, which correspond to the connecting rods 15, and operate the doors on their side of the car through the lever arms 23, which are pivoted to the shafts 24, the lever arms 25, connecting rods 26 and the lever arms 27, which are pivoted to shafts 28.

In order that the shaft 9 may be rotated it carries a sprocket wheel 29, upon which runs a chain 30. Attached to the two ends of the chain 30 are handles 31 and 32, and attached to the handles 31 and 32 is a cord 33, which runs around a pulley wheel 34. When the handle 32 is pulled down or the handle 31 is pulled up, the shaft 9 will be rotated so that its right hand threaded portion 10 will screw into the female screw 11, and move the lugs 12 toward the center of the car in the slots 14. At the same time the left hand threaded portion of the shaft 9, which corresponds to the portion desig-

dated by the numeral 10, will screw into its female screw and move the lugs 13 toward the center of the car in the same manner that the lugs 12 are moved. This movement 5 of the lugs 12 and 13, operating through the connecting rods 15 and 22, will open the doors 3 on both sides of the car.

Under ordinary conditions it is desirable that the doors 3 on one side of the car be locked in closed position, while the doors opposite are free to open and close. That this may be done, we provide the shaft case 5 with locking sleeves 35, and 36. The sleeve 35, which is held in place on the shaft case 5 by rings 37 and 38, is provided with slots 39, corresponding to the slots 14 in the shaft case 5, through which the lugs 12 may slide. Near the outer end of the sleeve 35 the slots 39 have enlargements 40, adapted to receive the lugs 12. If desired, the sides of the enlargements 40 may be slightly beveled, in order that the lugs 12 may be held tightly in position. We prefer that the enlargements 40 of the slots 39 shall be made to extend toward the bottom of the car on one side of the sleeve 35, and toward the top of the car on the other side of the sleeve 35. The sleeve 35 is provided with a guide ring 41, to assist in causing the lugs 12 to enter the enlargements 40, and a ring 42 may be attached to the lugs 12 adapted to slide along the sleeve 35 to hold the lugs 12 in correct relative position. In order to rotate the sleeve 35, it has near one 35 of its ends an upwardly extending arm 43, to which may be attached handles 44. If the sleeve 35 be rotated by one of the handles 44 when the doors are closed, the lugs 12 will enter into the enlargements 40 and 40 will thereby be prevented from sliding along the slots 14 in the shaft case 5, and will be held in fixed position. The sleeve 36 which is held in position by rings 45 and 46, is provided with slots and enlargements 45 similar to the slots 39 and enlargements 40 of the sleeve 35. It is also provided with an upwardly projecting arm 47, similar to the arm 43, to which are attached handles 48. When it is desired that the doors on 50 both sides of the car may be opened simultaneously, the sleeves 35 and 36 are rotated so that the lugs 12 and 13 will be free to move in their respective slots in the shaft case 5. If it is desired to have the doors on 55 one side of the car locked, the sleeve on that side of the car is rotated so that it embraces the lugs projecting from the female screw member on that side of the car. The sleeve on the opposite side of the car is left in its 60 original position. When the sleeves 35 and 36 are arranged in the manner which has just been described, and the shaft 9 is rotated, it is evident that both its right and left hand threaded portions will screw into

their respective female screws, but as one of the female screws is locked in place by its corresponding sleeve, the shaft 9 will move laterally in the shaft case 5, as shown in Fig. 5. The lateral movement of the shaft 9 will not be obstructed by the sprocket 70 wheel 29, owing to the gap between the two portions of the shaft case 5, within which gap the sprocket wheel will move. Owing to the lateral movement of the shaft 9, it will require but half as great a rotation of 75 the shaft 9 to open the doors on one side of the car as is required to open the doors on both sides of the car simultaneously.

As shown in Figs. 1 and 2 we provide steps outside of the doors 3 that may be 80 operated simultaneously with the doors 3, by any well known form of mechanism.

It is evident that many variations may be made in the arrangements of our mechanism without departing from the spirit of 85 our invention, since

What we claim is:

1. The combination of a car, doors on opposite sides of said car, operating means adapted to open the doors on both sides of 90 said car simultaneously and selective means adapted to lock the door on one side of the car and leave the door on the opposite side of the car free to be opened by said operating means.

2. The combination of a car, doors on opposite sides of said car, levers attached to said doors, operating means adapted to move the said levers to open the said doors on both sides of the car simultaneously, and 100 selective means whereby the door on one side of the car may be locked while the door on the opposite side of the car is being opened by said operating means.

3. The combination of a car, doors on 105 opposite sides of said car, a control handle at all times connected with said doors, and selective means whereby the door on one side of the car may be opened by said control handle without opening the door opposite.

4. The combination of a car, doors on opposite sides of said car, operating mechanism connected with said doors, a control handle connected with said operating mechanism whereby the doors on both sides of the car may be opened simultaneously, and selective means adapted to lock the door on one side of the car and divert all of the movement of said operating mechanism to 110 the door opposite.

5. The combination of a car, doors on opposite sides of said car, a shaft between the said doors, a right hand threaded portion at one end of the said shaft, a left hand threaded portion at the other end of said shaft, threaded blocks adapted to 120 contact with the said threaded portions of the

said shaft, levers connecting said doors and said blocks and means for rotating the said shaft.

6. The combination of a car, doors on opposite sides of said car, a shaft between the said doors, a right hand threaded portion at one end of the said shaft, a left hand threaded portion at the other end of said shaft, threaded blocks adapted to ¹⁴ act with the said threaded portions of the said shaft, levers connecting said doors and

said blocks, means for rotating said shaft and selective means whereby one of said blocks may be held in fixed position.
